OUTRIGGER CLIP

Charles W. Kravitch, Pittsburgh, Pa.

Application April 1, 1957, Serial No. 45,519

Term of patent 14 years

(Cl. D31—4)

Fig. 1

Fig. 2

Figure 1 is a plan view of an outrigger clip showing my new design.

Figure 2 is a perspective view of an outrigger clip illustrated in Figure 1.

The other side of said outrigger clip is substantially like the side shown.

I claim:

The ornamental design for an outrigger clip, substantially as shown and described.
